(57) **CLAIM**

I claim the ornamental design for a driving wrench, as shown and described.

DESCRIPTION

FIG. 1 is a top, front, right perspective view of a driving wrench showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom, front, left perspective view showing the driving wrench in use.

The dash-dash broken lines in the drawings illustrate portions of the driving wrench which form no part of the claimed design.

The dot-dashed line in the figures defines the boundary of claimed design and forms no part of the claimed design.

The driving wrench is shown with symbolic breaks in its length. The appearance of any portion of the article between the break lines forms no part of the claimed design.
